UNITED STATES PATENT OFFICE

167,803

FISHHOOK SHIELD

Royal A. Miller, Metamora, Ohio

Application February 9, 1952, Serial No. 18,452

Term of patent 14 years

(Cl. D31—4)

To all whom it may concern:

Be it known that I, Royal A. Miller, a citizen of the United States of America, residing at Metamora, Fulton County, Ohio, have invented a new, original, and ornamental Design for a Fishhook Shield, for which the following is a specification, reference being had to the accompanying drawings, forming part thereof, and

In the drawing:

Fig. 1 is a top plan view of a fishhook shield embodying my new design;

Fig. 2 is a view on the line II—II, Fig. 1;

Fig. 3 is a bottom plan view of the device of Fig. 1;

Fig. 4 is a view on the line IV—IV, Fig. 1; and

Fig. 5 is a perspective view of the fishhook shield.

I claim:

The ornamental design for a fishhook shield, substantially as shown.

ROYAL A. MILLER.
